(57) **CLAIM**

The ornamental design for a rainwater collecting device, as shown and described.

DESCRIPTION

FIG. 1 is a front, top and left side perspective of the rainwater collecting device showing the removable panel in place; FIG. 2 is a front elevation of the rainwater collecting device; FIG. 3 is a left side elevation of the rainwater collecting device;

FIG. 4 is a right side elevation of the rainwater collecting device;

FIG. 5 is a rear elevation of the rainwater collecting device; FIG. 6 is a top plan view of the rainwater collecting device;

FIG. 7 is a bottom plan view of the rainwater collecting device; and,

FIG. 8 is a front, top, left perspective of the rainwater collecting device with the removable panel removed therefrom.

The broken line showing is included for the purpose of illustrating and forms no part of the claimed design.
